FREQUENCY MODULATION DETECTOR AND CONVERTER

Robert B. Albright, Philadelphia, Pa., assignor to
Philco Radio and Television Corporation, Philadelphia, Pa., a corporation of Delaware

Application November 24, 1942, Serial No. 466,763

10 Claims. (Cl. 179—100.4)

This invention relates to frequency modulation systems, and more particularly to a novel circuit for detecting frequency-modulated carrier signals, and to means, including said detector circuit, for converting such signals to amplitude-modulated carrier signals having no substantial frequency modulation components.

The invention is applicable to frequency modulation systems generally, and it is readily adaptable to narrow-band frequency modulation systems, wherein the maximum frequency deviation may be of the order of a few kilocycles or less. Under these circumstances a frequency modulation detector of unusually high sensitivity is desirable in order to provide a satisfactory detected output from the relatively small deviations of the carrier wave. Aside from its evident use in frequency modulation communication channels, the circuit of the present invention is adaptable to various special applications of which one will be described in detail.

The principal object of the invention is to provide a novel frequency modulation detector employing a bridge network as a frequency-discriminator to obtain an amplitude modulation component corresponding to the frequency modulation of the signal to be detected.

Another object of the invention is to provide a frequency modulation detector of this character in which the bridge network is operated over a linear frequency range on one side of the null frequency (balance) point of the bridge.

A further object of the invention is to provide a frequency modulation detector employing either a bridged T network or a parallel T network for the stated purpose.

Another object of the invention is to provide a frequency modulation detector of simple low-cost construction.

Still another object of the invention is to provide a frequency modulation detector employing a frequency discriminating network which possesses a very steep frequency response characteristic over a specified range, thereby to provide high detector-sensitivity within said range.

The invention itself, as well as other of the objects thereof, will be understood by those skilled in the art from a consideration of the following description and accompanying drawings, in which:

Fig. 1 is a schematic illustration of a circuit utilizing the invention;

Fig. 2 shows a typical frequency response characteristic for the frequency discriminating network employed in the present invention;

Fig. 3 illustrates a modified portion of the circuit of Fig. 1;

Fig. 4 is a schematic illustration of a detector circuit embodying the invention;

5 Fig. 5 illustrates an alternative form of the bridge network employed;

Fig. 6 is a schematic illustration of a push-pull form of the invention; and

Fig. 7 shows the frequency response characteristics for the two frequency discriminating networks employed in the embodiment of Fig. 6.

Referring to Fig. 1 of the drawings, the frequency modulation detector per se, as it constitutes a part of the invention, comprises the frequency discriminating network 1, the grid-condenser grid-leak combination 2—3, and the input elements (i. e. the grid 4 and cathode 5) of the vacuum tube 6. The frequency discriminating network 1 consists of a pair of series condensers each of value

$$\frac{C}{2}$$

25 an inductance coil L having a resistance R, and a resistor 4R in shunt with the said series condensers. The resonant frequency of the network is substantially equal to the inverse of

$$2\pi\sqrt{LC}.$$

30 A typical frequency response characteristic of the network 1 is illustrated by the full-line curve A in Fig. 2. In a bridged T network of this character, wherein the shunt resistor has a resistance equal to four times the resistance R of the coil L, the ratio of output to input voltage (i. e.

35 "gain") at the resonant frequency is substantially zero. If, as is preferred, a coil L of relatively high Q is employed so that its resistance R is small, the response of the network will rise

40 steeply and linearly over a substantial range before flattening out. Consequently, if a frequency-modulated carrier signal is applied to the input terminals of the network 1, and the resonant frequency of the network is adjusted so that the frequency deviations of the carrier occupy the linear portion of the network's characteristic, the frequency-modulated signal as derived from the output terminals of the network will be strongly amplitude modulated. The wave

45 at this point is a hybrid signal having both amplitude and frequency modulation components. This hybrid signal may be supplied to any suitable rectifier circuit such as a diode rectifier, or, as in this instance, a rectifier which comprises the cathode 5 and input grid 4 of the

tube 6, together with the associated grid condenser 2 and grid leak 3. The detected audio signal, which is derived from the amplitude modulation of the hybrid wave, is present at the input grid 4 and may be utilized directly, or employed to effect other desired functions, an example of which use will be described presently. If the audio signal is to be used directly, as in a frequency modulation receiver, it would be preferred to employ, in place of the grid-leak form of detector, the more conventional diode type of detector. This will be described hereinafter with particular reference to Fig. 4.

The quality of the bridged T type of network which makes its use in a frequency modulation detector highly advantageous is the unusual steepness of its frequency response characteristic in the region of resonance. The characteristic A shown in Fig. 2, based on actual measurements of a network embodied in a working model of the invention, illustrates how, within the space of four kilocycles, the response of the network changes linearly from approximately zero (at resonance) to 65 per cent before reaching the curved region of the characteristic. Since the linear portion of this characteristic extends over a frequency range of approximately four kilocycles the optimum operating point is at two kilocycles either side of resonance. A network having the characteristic shown in Fig. 2 will perform most satisfactorily for frequency modulated signals in which the deviation on either side of the ± 2 k. c. operating point does not exceed two kilocycles.

A comparison between the frequency response characteristic of the bridged T network and that of a simple series resonant circuit employing elements of comparable Q (ratio of reactance to resistance), is afforded by Fig. 2, in which the dashed-line curve B represents the characteristic of the latter circuit. It is immediately evident that curve B does not possess the long straight working range of the characteristic A, and it follows that from the standpoint of distortion-free operation the characteristic A is the preferred one. It is likewise evident that the frequency sensitivity of the bridged T network greatly exceeds that of the series resonant circuit, as is shown by the steepness of the slope of curve A as compared to the slope of curve B. Since 50 overall detector sensitivity is directly proportional to the frequency sensitivity of the frequency discriminating network, the superiority of the bridged T system is apparent.

While the bridged T network of the present invention provides improved performance over that obtainable from a simple series resonant circuit even when the bridging resistor is not precisely equal to four times the resistance R of the coil L, it will be understood that the response of the network at resonance falls to zero only when this preferred relationship is adhered to, and it is only under these conditions that the maximum linearity and steepness of the curve is obtained. In this regard it may be stated that the higher the Q of the inductance coil L, the steeper will be the curve A, and, hence, the greater the sensitivity of the detector.

As employed in Fig. 1, the improved frequency modulation detector is utilized as an element in a system for converting a frequency-modulated carrier signal of one frequency into an amplitude-modulated carrier signal of substantially different frequency. Referring again to Fig. 1, there is shown a first oscillator stage comprising the

oscillator tube 7 and its associated resonant circuit 8. Although the oscillator stage may be regarded broadly as any source of frequency-modulated signals, for purposes of illustration there is shown an oscillator whose frequency is varied by means of a frequency modulation phonograph pick-up of the type described in my co-pending application Serial No. 397,986, filed June 13, 1941. The coil 9, which forms a part of the resonant circuit 8, may consist of a small inductor whose inductance is adapted to be varied through the agency of a stylus indicated diagrammatically by the reference numeral 10. The frequency modulated output of the oscillator may conveniently be derived from the anode 11 of the tube 7, the anode load 12 being connected as shown for that purpose.

If, for example, the resonant frequency of the frequency discriminating network 1 is adjusted to 20 455 k. c., and if the linear portion of the characteristic extends to four kilocycles on either side of resonance (e. g., as indicated in Fig. 2), the resonant frequency of the circuit 8 may most advantageously be adjusted either to 453 k. c. 25 or 457 k. c., thus permitting a maximum frequency deviation of two k. c. on either side of the unmodulated carrier frequency while still remaining on the linear portion of the network's frequency response characteristic.

30 In order to convert the frequency-modulated signals supplied by the oscillator 7 to a strictly amplitude-modulated signal (as contrasted to the usual hybrid signal) a second oscillator circuit is required. The second oscillator may comprise a resonant circuit 13 in association with the oscillator elements 5, 14 and 15 of the multi-grid vacuum tube 6. In order to prevent undesired interaction between the two oscillators, the frequency of the second oscillator is preferably selected so that the harmonics of one oscillator do not correspond with the fundamental or harmonics of the other oscillator. In the particular example under consideration, the frequency of the second oscillator was adjusted to 1500 k. c.

45 As has already been indicated, in the operation of the circuit a detected audio frequency signal is present at the control grid 4 of the tube 6. Since this grid is interposed in the space current path of the oscillator, it is evident that the carrier frequency oscillations generated in the tube 6 will be amplitude-modulated by the audio signal voltage present on the grid 4. In this manner very substantial degrees of modulation may be secured without the need for complicated modulation circuits or apparatus.

55 A model of the circuit of Fig. 1 was constructed and employed in a "wireless" type of phonograph record player, the 457 k. c. frequency-modulated signal being converted to a 1500 k. c. amplitude-modulated signal with 30% modulation, the latter signal being supplied by way of the output winding 16 to a small antenna (not shown) and thence to the receiving antenna of a conventional broadcast band radio receiver. The electrical constants of the frequency discriminating network 1 were as follows: $L=1300$ microhenries, $C=47.5$ micromicrofarads, and $R=35$ ohms. The resonant frequency of the bridged T network was approximately 455 k. c.

60 The circuit of Fig. 1 can also be employed to effect amplitude modulation of a carrier wave without the necessity of passing through the frequency modulation step hereinbefore described. In this modification of Fig. 1, shown in Fig. 3, a carrier wave source 17 is employed to generate a

fixed frequency, e. g., 457 k. c. This source may comprise the oscillator 7—8 of Fig. 1 with its inductance remaining constant. The inductance L of the frequency discriminating network 1 is replaced by a phonograph pick-up element employing an inductance unit of the type already described with reference to coil 9 of Fig. 1, the phonograph stylus being diagrammatically indicated by the arrow 18. In this embodiment of the invention, the frequency of the signal applied to the input terminals of the network 1 is constant, but since the resonant frequency of the network 1 is made to vary, it follows that the carrier signal as derived from the output terminals of the network 1 will be amplitude-modulated in precisely the same manner that the frequency modulated signal was amplitude-modulated in the instance first described.

Reference has already been made to the use of the present invention in the detector stage of a conventional frequency modulation radio receiver. A circuit suitable for this purpose is illustrated in Fig. 4. The generalized source 19 of frequency modulated signals will ordinarily comprise the output stage of the receiver's intermediate frequency amplifier. To this source is connected the frequency discriminating circuit 1, already described with reference to Fig. 2. The signal rectifier in this instance consists of the diode D, the coupling condenser 2, and the diode load resistor 3. The detected output signal may be supplied to a suitable output circuit, e. g., the volume control potentiometer 20, by way of an intermediate frequency filter network 21—22, and the coupling condenser 23.

In wide band systems, the frequency discriminating network 1 is preferably designed to resonate at a higher frequency (e. g., 4.3 mc.) in order that the network may present a substantially linear frequency characteristic over the wide deviation range of the signal to be received. In addition, it may be necessary to employ resonant elements of lower Q than would be utilized in a narrow band system. The inductor L may conveniently be provided with a movable commutated iron core member 24, by means of which the network 1 may be brought to resonance at any predetermined frequency.

In Fig. 5, there is shown another form of bridge network which may be employed as the frequency-discriminating device. This device is a parallel T network and comprises a pair of T sections having their input and output terminals connected in parallel relation. One of the T sections comprises a pair of series condensers and a shunt resistor, while the other section comprises a pair of series resistors and a shunt condenser. This network can be balanced to give zero gain at a predetermined frequency as follows. The series condensers of the first T section should be of like capacity, and the capacity of each should be equal to one-half the capacity of the shunt condenser of the second T section. The series resistors of the second T section should be of like resistance, and the resistance of each should be equal to twice the resistance of the shunt resistor of the first T section. Finally, it is necessary that

$$R = \frac{1}{2\pi f C}$$

where f is the null frequency (i. e. the frequency at which the gain of the network is zero), R is the resistance of the shunt element of the first T section, and C is the capacity of the shunt element of the second T section.

In the use of this bridge network according to the invention, the operation takes place on one side of the null frequency point, as previously described. While this network does not exhibit the steep frequency characteristic of the bridged T network, it is well adapted for use in a frequency modulation detector, particularly in a wide band system.

It is important to note that the parallel T network does not require the use of inductance coils, but utilizes resistors and condensers related in a very simple manner. Hence, it is capable of easy and economic construction.

In a physical embodiment of this device, the electrical constants were as follows: $C=200$ micromicrofarads, and $R=2000$ ohms. The null or balance frequency of the network was 398 k. c.

Reference is now made to Fig. 6, in which there is illustrated a push-pull form of the detector circuit of Fig. 4. In the embodiment of Fig. 6 a pair of single-sided detector circuits (of the type illustrated in Fig. 4) are connected back-to-back to form a push-pull or balanced type of detector. While the push-pull form of the invention is not limited to the use of any particular type of single-sided bridge network, for purposes of illustration a pair of bridged T networks 1a and 1b have been shown. These networks are connected in push-pull relation to the source of frequency-modulated signals 19 through the agency of a transformer 25 having a center-tapped secondary winding. The detector diodes D₁ and D₂ are provided with load resistors 26 and 27 each shunted by the condensers 28 and 29 respectively. The diode load resistors 26 and 27 are connected to each other and to the output circuit 23, 20 in balanced relation.

Reference may be had to Fig. 7 for an illustration of the preferred mode of operation of the circuit of Fig. 6. Assuming that the center-frequency (the frequency of the undeviated frequency-modulated carrier) of the signal to be received is f_c , the bridge networks 1a and 1b are preferably balanced for zero transmission at the frequencies f_1 and f_2 respectively, said frequencies being respectively below and above the said center-frequency. The frequency characteristic of the bridged T network 1a is illustrated by the similarly designated curve of Fig. 7, while the frequency characteristic of the bridged T network 1b is designated 1b. In the preferred embodiment the crossover point 30 between the two frequency characteristics occurs at the frequency f_c , and at the mid points of the linear portions of the characteristics. The push-pull embodiment of the invention has the advantage that distortion resulting from nonlinearity of the networks is greatly minimized.

Although the invention has been described and illustrated with particular reference to certain preferred embodiments, it should be understood that numerous alterations and modifications may be made within the scope of the invention, as defined in the appended claims.

I claim:

1. In a phonograph record player, the combination comprising a first vacuum tube oscillator, a phonograph pickup device constructed and arranged to frequency-modulate the signal generated by said oscillator, a bridge network arranged to receive the frequency-modulated signal and adapted to function as a frequency discriminator, a second vacuum tube oscillator constructed and arranged to generate a carrier wave of substantially fixed frequency, and means responsive to a

signal derived from said bridge network for amplitude-modulating the carrier wave derived from said second vacuum tube oscillator.

2. In a phonograph record player, the combination comprising a source of carrier signal of fixed frequency, a resonant bridged T network connected to said source, a phonograph pickup device of the variable reactance type, said device constituting an element of said network, the resonant frequency of said network being varied at an audio frequency rate by the operation of said pickup, whereby the gain of said network, and hence the amplitude of the transferred carrier signal, is varied in substantial accordance with the reactance variations of said pickup.

3. In an electrical system, a source of frequency modulated signals, a first bridged T network balanced for substantially zero transmission at a predetermined frequency, a first rectifier means connected to the output terminals of said network, a second bridged T network balanced for substantially zero transmission at a different predetermined frequency, a second rectifier means connected to the output terminals of said second network, means for applying signals from said source to said bridged T networks in push-pull relation, and means connecting at least a portion of said rectifier means in balanced relation.

4. In a frequency-modulation detector, a frequency discriminating circuit comprising a bridged T network and rectifier means connected thereto, the constants of said network being so selected that its gain is substantially zero at one frequency, the gain varying substantially linearly from that frequency over a predetermined operating range, said range including the frequency range of the frequency-modulated signal to be detected.

5. In a frequency-modulation detector, a frequency discriminating circuit comprising a bridged T network whereof the upright of the T is an inductance coil, the arms of the T are condensers and the bridging element is a resistor whose resistance is substantially four times the resistance of the inductance coil, the constants of said network being so selected that its gain is substantially zero at one frequency, the gain varying substantially linearly from that frequency over a predetermined operating range which includes the frequency range of the frequency-modulated signal to be detected, and rectifier means connected to said network.

6. In a frequency modulation detector, a bridged T network adjusted to operate as a frequency discriminator over the frequency range of the signal to be detected, and a signal rectifier connected to the output terminals of said network, said network being characterized in that the arms of the T are capacitive, the upright element of the T is resistive and inductive, and the bridging element is resistive and is bridged across the capacitive arms.

7. A frequency modulation detector as claimed in claim 6, wherein the resistance of the bridging element is substantially four times the resistance of said upright element.

15 8. In a frequency modulation detector, a bridged T network adjusted to operate as a frequency discriminator over the frequency range of the signal to be detected, and a signal rectifier connected to the output terminals of said network, said network comprising a pair of series reactance elements constituting the arms of the T, a reactance element of different character in the upright of the T, and a resistance element bridged across said series reactance elements.

20 9. In a phonograph record player, the combination comprising a first oscillator, a phonograph pickup device constructed and arranged to frequency-modulate the signal generated by said oscillator, a frequency discriminator device arranged to receive the frequency-modulated signal, a second oscillator constructed and arranged to generate a carrier wave of substantially fixed frequency, and means responsive to a signal derived from said discriminator device for amplitude-modulating the carrier wave derived from said second oscillator.

25 10. In a phonograph record player, the combination comprising a source of carrier signal of fixed frequency, a resonant bridge network connected to said source, a phonograph pickup device of the variable reactance type, said device constituting an element of said network, the resonant frequency of said network being varied at an audio frequency rate by the operation of said pickup, whereby the gain of said network, and hence the amplitude of the transferred carrier signal, is varied in substantial accordance with the reactance variations of said pickup.

ROBERT B. ALBRIGHT.
